UNITED STATES PATENT OFFICE.

JOHN J. KEENAN, OF NEW YORK, N. Y.

EMERGENCY TRAFFIC BARRIER.

Application filed March 21, 1923. Serial No. 626,677.

To all whom it may concern:

Be it known that I, JOHN J. KEENAN, a citizen of the United States, and a resident of New York, in the county of New York and State of New York, have invented certain new and useful Improvements in an Emergency Traffic Barrier, of which the following is a full, clear, and exact specification.

- 10 This invention relates more particularly to an improved form of apparatus disclosed in Patent No. 1,203,006, dated October 31, 1916 and Patent No. 1,356,922, dated October 26, 1920.
- 15 My invention has for its object primarily to provide an apparatus designed to be employed across public highways, such as the streets of cities, at railroad crossings, on ferry boats and elsewhere, whereby automobiles, autotrucks and other vehicular traffic as well as runaway animals may be timely stopped in their course of travel to prevent the occurrence of accidents, and which is of an electrically operative form for allowing 20 the device to be operated from a station suitably located at a distance from the apparatus if desired. These advantages are effected mainly by the provision of spaced guard elements, each having a post with a 25 substantially U-shaped flange on one of its lengthwise edges and having an angularly disposed arm protruding from its other end. The guard elements are pivoted to the walls of a trough when arranged across a public 30 highway or on a ferry boat and elsewhere so that the posts are normally positioned lengthwise in the trough with the flanges being flush with the highway and so that the grooves of the flanges are in register, 35 while the arms of the guard elements are disposed interiorly of the trough. The guard elements are adapted to be swung whereby the posts will be moved to and from spaced vertical positions above the 40 highway for serving as a barrier to stop the travel of vehicles and animals in emergency.

Other objects of the invention are to provide electric means operative for causing the guard elements to be swung for alternately 45 raising and lowering the posts simultaneously; to provide a flexible barrier line which is normally disposed in the grooves of the flanges of the posts when lowered in the trough for being moved to a position on the upper ends of the posts when raised above the highway to prevent persons

from passing through the spaces between the posts and to provide a traffic barrier of a simple, efficient and durable construction which may be made of suitable material in any appropriate size.

With these and other objects in view, the invention will be hereinafter more fully described with reference to the accompanying drawings forming a part of this specification in which similar characters of reference indicate corresponding parts in all the views, and will then be pointed out in the claims at the end of the description.

In the drawings, Figure 1 is a fragmentary view, partly in section, showing one end of a ferry boat with one form of my improved emergency barrier applied thereto.

Fig. 2 is an enlarged fragmentary view showing a detail section taken on the line 75 of 2-2 of Fig. 1.

Fig. 3 is a fragmentary view showing a diagrammatic view of the electric circuit, motor and controlling switch used for operating the apparatus.

Fig. 4 is an enlarged fragmentary detail sectional view showing the parts of the apparatus illustrated in Fig. 2 when operated and in position for stopping traffic in emergency.

Fig. 5 is an enlarged fragmentary view, partly in detail and partly in section, taken on the line 5-5 of Fig. 2, and

Fig. 6 is an enlarged fragmentary view showing a detail section taken on the line 90 6-6 of Fig. 2.

When the apparatus or traffic barrier is constructed for use a trough, as 10, having a bottom 11 and side walls 12, 13 is arranged in a sunken position across a public highway, such as the street of a city, railroad crossing and elsewhere, though in the drawing the apparatus is illustrated as employed on a ferry boat, as 14, with the trough 10 being sunken in the deck 15 across one end of the vehicular traffic passage way, as 16.

In the trough 10 are a series of guard elements 17, all preferably of corresponding sizes and formations, and each of these guard elements has a post 18 with a grooved or substantially U-shaped flange 19 extending lengthwise of one of its edges, and protruding from one end of each post right angularly to its edge opposite to the grooved flange is an arm 20. The juncture of these parts of the posts 18 and arms 20 of each

of the guard elements is pivoted, at 21, to the side walls 12, 13 of the trough 10 so that the posts are disposed lengthwise of the trough and so that the flanges 19 are flush with the surface of the highway with the grooves of the flanges being in register. The arms 20 of the guard elements extend vertically downward in the trough, and the posts 18 of the guard elements are of lengths 10 so that their ends are in close proximity as well as extending practically throughout the entire length of the entrance of the trough. Protruding right angularly from the lower part of the arm 20 of each of the guard elements 17 in an opposite direction to the posts 18 in an extension member or second arm 22, and these extension members are in alignment within the trough. All of the extension members 22 are pivoted, at 23, to a 20 single bar, as 24, so that by moving this bar in a longitudinal plane in one direction the guard elements will be swung on the pivots 21 for causing the posts 18 to be moved to spaced vertical positions above the highway, as shown in Fig. 4, for stopping traffic on the highway as occasion requires, and by reversely moving the bar 24 the guard elements will be swung to lower the posts so that the flanges 19 are on a level with the 30 surface of the highway.

In order to prevent persons from passing through the space between the posts of the guard elements when moved to upstanding positions above the highway, a flexible line barrier, as 25, is provided. This line barrier is preferably in the form of a chain or cable having its ends fastened, at 26, 27, to suitable supports, as 28, 29, provided on the highway contiguous to the ends of the guard 40 elements 17 so that when the elements are in lowered positions in the trough the line barrier will lie in the grooves of the flanges 19 of the posts 18, as shown in Figs. 1 and 2, for being elevated whereby the line barrier will be disposed on the tops of the posts when in upstanding positions. The line barrier will then obstruct the passage of persons through the spaces between the posts.

Serving to operate the guard elements 17 and line barrier 25, as explained, I provide electric operative means, which preferably includes two drums or pulleys 31, 32 provided in the trough 10 in spaced relation to the ends of the bar 24 of the guard elements. The drum 31 is held on a shaft 33 journaled in the bearings of two spaced brackets, as 34, 35, which are arranged on the bottom of the trough, and the drum 32 is held on a shaft 36 journaled in the bearings of two spaced brackets 37, 38 also arranged on the bottom of the trough. On the drums is wrapped a cable 39 having its ends attached to the ends of the bar 24 of the guard elements.

The shaft 36 of the drum 32 is adapted to

be driven by a suitable reversible type of electrically operative motor, as 42, which may be mounted on the bottom of the trough 10. On the drive shaft of the motor is a worm, as 43, in mesh with a worm gear 44 held on the shaft 36 of the drum 32. The motor is interposed in a normally open electric circuit 45 which may be composed of a wire 46 leading from a battery 47 or other source of electrical energy to one terminal of the motor. A wire 48 leads from the battery to one pole of a controlling switch 49 which may be of any well known make operative for closing and opening the circuit whereby the motor may be revolved in either direction and from the second pole of the switch leads a wire 50 to the second terminal of the battery. The switch 49 may be arranged to allow the apparatus to be operated at a distant or nearby station, and when the switch is operated accordingly for operating the guard elements and line barrier to close the passage on the highway, the circuit will be closed from the battery 47 over wire 46 to one terminal of the motor. From the battery the circuit will also be closed over wire 48 and through the switch and over the wire 50 to the second terminal of the motor. The motor will then be driven to rotate the worms 43, 44 for revolving the shaft 36 and drums 32 so that the cable 31 and bar 24 will operate in unison all of the guard elements whereby the posts 18 will be swung to upstanding positions above the highway with the barrier line 25 being stretched across the tops of the posts. When the switch is operated to close the circuit for reversely rotating the motor, the drums and cable will be operated for causing return of the guard elements and the barrier line to their normal positions in the trough.

While in the foregoing description, I have embodied the preferred form of invention, I do not wish to be understood as limiting myself thereto, as I am aware that modifications may be made therein without departing from the principle or sacrificing any of the advantages of this invention, therefore, I reserve to myself the right to make such changes as fairly fall within the scope thereof.

Having thus described my invention, I claim as new and desire to secure by Letters Patent:

1. In an emergency traffic barrier, the combination with a trough adapted to be arranged across a highway so that the walls thereof are below the surface of the highway, of spaced guard elements, each having a post with a substantially U-shaped flange 125 on one of its lengthwise edges, said elements pivoted to the walls of the trough whereby the posts thereof are normally positioned lengthwise in the trough with the flanges being flush with the surface of the 130

- highway and so that the grooves of the flanges are in register, a flexible barrier line normally disposed in the grooves of the flanges of the posts when lowered in the trough and the line having its ends held above both of the end guard elements for being moved to and from a position on the upper ends of the posts, when raised and lowered above the highway, and electric means operative for operating the guard elements whereby the posts will be swung to and from spaced vertical positions above the highway.
2. In an emergency traffic barrier, the combination with a trough adapted to be arranged across a highway so that the walls thereof are below the surface of the highway, of spaced guard elements, each having a post with a substantially U-shaped flange on one of its lengthwise edges and having an angularly disposed arm protruding from its other end, said elements pivoted to the walls of the trough whereby the posts thereof are normally positioned lengthwise in the trough with the flanges being flush with the surface of the highway and so that the grooves of the flanges are in register while the arms of the elements are interiorly of the trough, a flexible barrier line normally disposed in the grooves of the flanges of the posts when lowered in the trough and the line having its ends held above both of the end guard elements for being moved to and from a position on the upper ends of the posts when raised and lowered above the highway, an extension member disposed angularly from the arm of each of the guard elements, a bar in the trough, having all of the extension members pivoted thereto, two drums revolvably supported in the trough in spaced relation to the ends of the bar and also spaced from the end guard elements, a cable wrapped on the drums, and having its ends attached to the ends of said bar, and electric means operative for revolving the drums to move the cable and said bar for operating the guard elements whereby the posts will be swung to and from spaced vertical positions above the highway.
3. In an emergency traffic barrier, the combination with a trough adapted to be arranged across a highway so that the walls thereof are below the surface of the highway, of spaced guard elements, each having a post with a substantially U-shaped flange on one of its lengthwise edges and having an angularly disposed arm protruding from its other end, said elements pivoted to the walls of the trough whereby the posts thereof are normally positioned lengthwise in the trough with the flanges being flush with the surface of the highway and so that the grooves of the flanges are in register while the arms of the elements are interiorly of the trough, a flexible barrier line normally disposed in the grooves of the flanges of the posts when lowered in the trough and the line having its ends held above both of the end guard elements for being moved to and from a position on the upper ends of the posts when raised and lowered above the highway, an extension member disposed angularly from the arm of each of the guard elements, a bar in the trough, having all of the extension members pivoted thereto, two drums revolvably supported in the trough in spaced relation to the ends of the bar and also spaced from the end guard elements, a cable wrapped on the drums, and having its ends attached to the ends of said bar, and electric means operative for revolving the drums to move the cable and said bar for operating the guard elements whereby the posts will be swung to and from spaced vertical positions above the highway.
5. In an emergency traffic barrier, the combination with a trough adapted to be arranged across a highway so that the walls thereof are below the surface of the highway, of spaced guard elements, each having a post with a substantially U-shaped flange on one of its lengthwise edges and having an angularly disposed arm protruding from its other end, said elements pivoted to the walls of the trough whereby the posts thereof are normally positioned lengthwise in the trough with the flanges being flush with the surface of the highway and so that the grooves of the flanges are in register while the arms of the elements are interiorly of the trough, the guard elements adapted to be swung whereby the posts will be raised and lowered to and from spaced vertical positions above the highway, a flexible barrier line normally disposed in the grooves of the flanges of the posts when lowered in the trough and the line having its ends held above both of the end guard elements for being moved to and from a position on the upper ends of the posts when raised and lowered above the highway.

highway, an extension member disposed angularly from the arm of each of the guard elements, a bar in the trough, having all of the extension members pivoted thereto, two drums revolvably supported in the trough in spaced relation to the ends of the bar and also spaced from the end guard elements, a cable wrapped on the drums and having its ends attached to the ends of said bar, a motor in the trough, operative for revolving the drums to move its cable and the bar whereby the guard elements may be swung

for moving the posts and barrier line above the trough and highway, an electric circuit leading to the motor, and a controlling switch operative for closing and opening the circuit to operate and stop the motor.

This specification signed and witnessed this 20th day of March A. D. 1923.
